UNITED STATES PATENT OFFICE.

FRANK A. SMITH, OF GALION, OHIO.

DESIGN FOR A JAW FOR PIPE-WRENCHES.

SPECIFICATION forming part of Design No. 31,940, dated December 5, 1899.

Application filed November 10, 1899. Serial No. 736,564. Term of patent 14 years.

To all whom it may concern:

Be it known that I, FRANK A. SMITH, a citizen of the United States of America, residing at Galion, in the county of Crawford and State of Ohio, have invented and produced a new and original Design for a Jaw for Pipe-Wrenches, of which the following is a specification, reference being had therein to the accompanying drawings, forming a part thereof, in which—

Figure 1 is a side elevation of the jaw, showing my new design; and Fig. 2 is an end elevation thereof.

As shown in the drawings, the leading or material feature of my design consists in the T-shaped configuration and outline as produced by the head A of the member in connection with the arms or shanks B.

The head A in plan has substantially the

shape of an ellipse divided in half on its major axis with the corners cut off and the straight face a provided with serrations.

The shanks B are at right angles to the head and form between them an open slot b for receiving the fixed member of the wrench between them.

Having described my invention, what I claim as new, and desire to secure by Letters Patent, is—

The design for a jaw for pipe-wrenches, as herein shown and described.

In testimony whereof I affix my signature in presence of two witnesses.

FRANK A. SMITH.
